US0D1038761S

(12) **United States Design Patent** (10) **Patent No.:** **US D1,038,761 S**
(45) **Date of Patent:** **** Aug. 13, 2024**

(54) **BOTTLE**

(71) Applicant: **Closure Systems International Inc.**,
Indianapolis, IN (US)

(72) Inventor: **Alex E. Kittleson**, West Lafayette, IN
(US)

(73) Assignee: **CLOSURE SYSTEMS
INTERNATIONAL INC.**, Indianapolis,
IN (US)

(**) Term: **15 Years**

(21) Appl. No.: **29/871,121**

(22) Filed: **Feb. 13, 2023**

(51) **LOC (14) Cl.** **07-01**

(52) **U.S. Cl.**

USPC **D9/557**; D9/502; D9/539

(58) **Field of Classification Search**

USPC D9/499, 500, 503, 504, 516, 529, 549,
D9/550, 558, 574, 575, 502, 555, 556,
D9/557, 530, 537, 538, 542, 738, 761,
D9/539; D7/602, 612, 615

CPC B65D 1/02; B65D 23/102; B65D 1/0246

(74) *Attorney, Agent, or Firm* — NIXON PEABODY LLP

(57) **CLAIM**

The ornamental design for a bottle, as shown and described.

DESCRIPTION

FIG. 1 is a top perspective view of a bottle, showing my new design.

FIG. 2 is a front view of the bottle of FIG. 1.

FIG. 3 is a back view of the bottle of FIG. 1.

FIG. 4 is a first side view of the bottle of FIG. 1.

FIG. 5 is a second side view of the bottle of FIG. 1, which is the opposite of the first side view.

FIG. 6 is a top view of the bottle of FIG. 1; and,

FIG. 7 is a bottom view of the bottle of FIG. 1.

The broken lines are shown for the purpose of illustrating parts of the article that form no part of the claim.

1 Claim, 7 Drawing Sheets
